US00D794606S

(12) **United States Design Patent** (10) Patent No.: **US D794,606 S**
(45) Date of Patent: **** Aug. 15, 2017**

(54) **GIMBAL WITH HANDLE**

(71) Applicant: **SZ DJI Osmo Technology Co., Ltd.**,
Shenzhen (CN)

(72) Inventors: **Haibin Zheng**, Shenzhen (CN); **Min Kim**, Shenzhen (CN)

(73) Assignee: **SZ DJI Osmo Technology Co., Ltd.**,
Shenzhen (CN)

(**) Term: **15 Years**

(21) Appl. No.: **29/566,534**

(22) Filed: **May 31, 2016**

(51) LOC (10) Cl. **14-03**

(52) U.S. Cl.

USPC **D14/217**

(58) **Field of Classification Search**

(57) **CLAIM**

The ornamental design for a gimbal with handle, as shown and described.

DESCRIPTION

FIG. 1 is a top front perspective view of a gimbal with handle showing the claimed design;

FIG. 2 is a top rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the figures show portions of the gimbal with handle that form no part of the claimed design.

1 Claim, 7 Drawing Sheets
